UNITED STATES PATENT OFFICE.

ROBERT LEE HORSLEY AND JAMES H. ROUNTREE, OF WHITNEY, TEXAS.

WATER-RESERVOIR FOR STOVES.

SPECIFICATION forming part of Letters Patent No. 643,136, dated February 13, 1900.

Application filed April 17, 1899. Serial No. 713,425. (No model.)

To all whom it may concern:

Be it known that we, ROBERT LEE HORSLEY and JAMES H. ROUNTREE, citizens of the United States, residing at Whitney, county 5 of Hill, and State of Texas, have invented a new and useful Improvement in Water-Reservoirs for Stoves, to be known as the "Top Reservoir," which is fully set forth in the following specification, reference being had to 10 the annexed drawings.

This invention relates to water-reservoirs, and more particularly to that class adapted for heating water in connection with a common form of stove in which the smoke-pipe 15 is exposed.

One object of the invention is to provide a reservoir which will have such shape as to occupy a minimum of space upon the top of the stove about the smoke-pipe and which 20 will at the same time hold a maximum of water without interfering with the placing of tall vessels upon the stove.

A further object of the invention is to so form the reservoir as to insure an efficient 25 circulation of water during the heating operation and in which the bubbling at the surface of the water will not have a splashing effect, the upper end of the reservoir being extended laterally to form a shelf.

30 In the drawings forming a portion of this specification, and in which similar numerals of reference designate corresponding parts, Figure 1 is a perspective view of the reservoir applied to a stove. Fig. 2 is a trans- 35 verse section of the reservoir and connected portions of the stove and stovepipe.

Referring now to the drawings, the reservoir consists of a base 5, which may have any desired outline, although in this instance 40 it is shown as rectangular and oblong. From the sides of the base 5 there are extended upwardly the side pieces 6, which are similar in form and the side edges of which lie parallel for a distance of substantially two- 45 thirds of its height, after which the side edges are diverged, as shown. From the ends of the base 5 are extended upwardly additional side pieces 7, having parallel side edges and which are soldered or otherwise secured to 50 the edges of the side pieces 6, the result being a receptacle having a constant rectangular cross-section throughout the lower two-

thirds of its height and above which it is gradually expanded throughout the remainder of its height.

55

Fixed to the upper edges of the side pieces 6 is a single top section secured at its ends to said side pieces, said top section having lids 9 hinged to its side edges and adapted, in connection with the said top section, to form 60 a complete cover or lid for the receptacle.

Centrally of the bottom 5 is formed an elliptical opening, the major diameter of which lies in the direction of flare of the receptacle, and registering with this opening is a circular 65 opening 10 in the top section 8. Connecting the openings 10 and 11 is a tube 12, the lower end of which is elliptical and the upper end of which is circular, and which tube forms a vertical passage through the receptacle.

In one side 6 of the receptacle is entered a faucet 14, near the lower edge thereof, and through the medium of which water which has been contributed to the vessel through 75 the top may be withdrawn.

In practice the receptacle is disposed with the tube 12 to receive the projecting elliptical tube upon a stove and to which the stovepipe is ordinarily connected, and into 80 the upper end of the tube is passed the end of a stovepipe 15, or, if desired, the receptacle may be disposed with the tube 12 upon the stovepipe. A quantity of water is then placed within the receptacle and preferably 85 to reach adjacent the upper end thereof, which water will receive heat through the tube 12, as will be readily understood.

With the interior shape of this device there will be an efficient circulation of water, the 90 water directly adjacent the tube or pipe 12 rising along the surface of said tube or pipe, from which it will pass outwardly, due to the bubbling of the water and to the well-known laws of circulation of water when heated, 95 and will then pass downwardly of the surface of the receptacle and to the bottom thereof, when it will again rise along the surface of the tube.

It will be noted that the bottom of the tube 100 12 is separated from the walls of the receptacle by an interspace and that the tapering of the tube results in a gradually upwardly expanding effective cross-section of the re-

ceptacle. Owing to this construction there is a minimum retarding of the upward flow of water by the cooler water falling at the wall of the receptacle and a resultant more efficient circulation. Moreover, as each particle of water rises it is added to the quantities rising thereabove, so that the cross-section of the rising column increases upwardly. This is compensated for by the gradual expansion of the effective cross-section. Furthermore, the flared upper end of the vessel prevents any objectionable effects of bubbling, as will be readily understood, and at the same time the specific shape of the vessel enables it to hold a maximum quantity of water while occupying a minimum of space upon the top of the stove and without interfering with the placing of tall vessels.

It will thus be seen that the structure presented accomplishes the results for which it is designed and that the efficient circulation

results in a quick heating of the water within the receptacle.

Having thus described the invention, what is claimed is—

25 A water-reservoir consisting of a vessel or receptacle, the lower portion of which is a parallelogram, two of the sides of which extend upwardly and parallel to the top of the vessel, the remaining sides of the upper portion of the vessel being flared outwardly and upwardly, and an upwardly-tapering and vertical tubular passage passing through said receptacle and having its entire wall separated from the walls of said receptacle by an interspace.
